WARE

CHARGE FORMING DEVICE

Application filed June 27, 1928. Serial No. 288,685.

This invention relates to charge forming devices for internal combustion engines and more particularly to the type of charge forming device comprising a plurality of 5 primary fuel mixing chambers or primary carburetors, one for each intake port of the engine and cooperating respectively with a plurality of secondary fuel mixing chambers or secondary carburetors each located adjacent an engine intake port and receiving fuel air mixture from a pipe connected with one 10 of the primary carburetors while receiving air when required through one branch of an air manifold which supplies air to all the 15 secondary carburetors. The primary carburetors receive liquid fuel from a common fuel bowl in which the level is controlled by a float valve.

Examples of charge forming devices of 20 the character described above are disclosed in the copending applications of W. H. Teeter, Serial No. 221,372, filed September 22, 1927 which matured to Patent No. 1,819,526 granted August 18, 1931 and W. H. Teeter, 25 Fred E. Aseltine and Carl H. Kindl, Serial No. 288,683, filed June 27, 1928. In these charge forming devices a plurality of primary carburetors are provided one for each intake port. The fuel mixture from 30 the primary carburetors is conveyed to secondary mixing chambers located adjacent the various engine intake ports where it is mixed with air. Throttling of the engine is effected by a single primary throttle which 35 controls all the primary carburetors, and a single main throttle controlling the air flow through the main air manifold. These throttles are operated from a common operating mechanism which is so arranged 40 that the primary throttle controls the quantity of mixture passing to the engine at speeds up to a vehicular speed of 20-25 miles per hour, after which the main air throttle begins to open and becomes the main controlling element regulating the mixture out 45 flow.

The general objects of the charge forming devices disclosed in the applications referred to are, first, to provide a mixture of fuel and air having the desired fuel and air ratio

under all operating conditions, and, second, to deliver equal quantities of this mixture to each cylinder of the engine under various conditions of load and speed, without requiring the heating of the fuel or fuel mixture before it is delivered to the engine. 55

Various devices are provided in these charge forming devices for controlling the flow of fuel and air under various operating conditions so as to secure at all times a mixture having the desired fuel and air ratio. Certain of these flow proportioning devices are made necessary because the air flowing through the primary carburetors moves past the jets at such high velocity that it creates 60 at said jets a velocity head which is effective to cause flow of fuel therefrom. This velocity head which is present at the fuel jets causes a too rapid increase in fuel flow on 65 increase of engine speed resulting in too rich a fuel mixture unless some means is provided to compensate therefor. Because the excess of fuel in the mixture is a variable 70 thing dependent on a number of different factors it has been found almost impossible to correct the effect of the velocity head on 75 fuel flow by any one device, and very difficult to secure a mixture having the desired fuel and air ratio under all operating conditions 80 by use of any proportioning devices heretofore known. 85

The charge forming device forming the subject of the present invention is of the same general type as those disclosed in the above mentioned applications and the principal object of this invention is to provide a charge forming device of this character in which fuel is caused to flow from the jets by the static suction within the carburetor, and in which the effect of velocity head on the fuel flow is substantially eliminated under all operating conditions. A further object of the invention is to provide a charge forming device having improved and simplified mechanism for proportioning the fuel mixture so as to provide fuel mixtures of the desired proportions to most successfully operate the engine under all possible operating conditions. Further objects of the invention are to provide a charge forming device of the charac- 90 95 100

ter described which has the same capacity as those heretofore designed, but is considerably reduced in size and to improve and simplify the construction throughout whereby the cost of manufacturing is materially reduced and to provide a device of this character having a substantially symmetrical design.

With these objects in view one feature of the invention resides in the provision of a plurality of fuel jets to each of which the static suction of the main air chamber is communicated through a passage of considerably greater area than the outlets through which fuel flows into the high velocity air current passing through each primary carburetor. By means of this construction the static suction of the main air chamber is made the principal factor controlling the flow of fuel at all engine speeds.

A further feature of the invention consists in the provision of means, normally ineffective, but rendered effective by the choke device, to admit a small quantity of air to carry the starting fuel to the engine when the main air valve is held closed by said choke device when the engine is to be started.

A further feature of the invention is a novel form of accelerator pump for supplying a predetermined quantity of additional fuel for acceleration whenever the throttle is opened, irrespective of the position of the throttle at the beginning of its opening movement.

A further feature of the invention resides in the provision a simplified form of secondary air valve and dash pot controlling the movements thereof.

An improved and simplified mechanism for connecting the primary and secondary throttles to a common operating means forms a still further feature of the invention.

Still further features of the invention reside in the provision of means connecting the primary carburetors with the main air chamber whereby substantially all the air entering the primary carburetor must come from the main chamber, and an improved form of fuel inlet means which admits fuel to each primary mixture passage which comprises a plurality of fuel ports in the wall thereof between the inlet end of said passage and the primary throttle.

The present invention is embodied in a charge forming device comprising an air manifold which does not include any of the control mechanism of the carburetor, and a main carburetor unit adapted to be attached to and supported by the air manifold, said unit including the fuel bowl, the primary carburetors to which liquid fuel is distributed from the fuel bowl, and all of the valves and control mechanism associated therewith for controlling the flow of air through the air manifold and the flow of primary fuel mix-

ture from the primary carburetors to the secondary carburetors at each engine intake port. The primary mixture is conducted from the primary carburetors to each of the secondary carburetors through pipes constructed in a manner described in detail hereinafter and communicating with three passages in the manifold wall which register, when the carburetor unit is attached to said manifold with the primary mixture passages in said unit. In this way the carburetor unit may be readily attached to or detached from the air manifold, permitting the manufacture of the air manifold as separate units.

Further objects and advantages of the present invention will be apparent from the following description, reference being had to the accompanying drawings, wherein a preferred form of embodiment of the invention is clearly shown.

In the drawings:

Fig. 1 is a plan view of a form of the present invention.

Fig. 2 is a front elevation of the device shown in Fig. 1.

Fig. 3 is an elevation of the carburetor unit viewed from the left in Fig. 1, partly broken away to show certain parts in section.

Fig. 4 is a view similar to Fig. 3 viewed from the right in Fig. 1.

Fig. 15 shows a modified form of fuel jet.

Fig. 16 is a diagrammatic, sectional view illustrating all of the fuel passages supplying fuel to any one of the primary carburetors.

Referring to the drawings and more particularly to Fig. 1, the reference number 20 designates an air manifold having an inlet 22 communicating with the main outlet 22 of the carburetor unit, (see Fig. 6) and three outlet pipes 24, each adapted to be connected to one of the intake ports of the engine (not shown). Each of the intake ports is adapted

to supply fuel mixture to two adjacent cylinders of the engine. The air manifold 20 is adapted to be secured to the cylinder block in the same way as the conventional intake manifold is attached to the cylinder head. 5 Adjacent its intake the manifold 20 is provided with a flange 26 to which may be secured the carburetor unit which will now be described.

10 The carburetor unit comprises two main castings, a housing 28, and a frame 30, positioned just below the housing and secured thereto by screws 32, see Figs. 2 and 4. The housing 28 is provided with a flange 34 which 15 is attached to the manifold flange 26 by screws 36 when the device is assembled. The housing 28 contains the main air chamber, air inlet valve, primary carburetors, throttles and other mechanism later described, 20 while the frame 30 has formed therein various dash pots for controlling admission of air and other devices more fully described hereinafter. In addition the frame 30 provides the top for a constant level fuel chamber formed by a sheet metal fuel bowl 38, the upper edge of which fits against a shoulder 40 formed on a projecting flange 42 of the frame 30, the bowl being held tight against the shoulder 40 by a screw 44, screwed 25 into the frame 30. A gasket 46 is provided between the head of screw 44 and the bowl to prevent leakage and a gasket may be fitted on shoulder 40 if desired. A gasket 48 is provided between the housing 28 and 30 frame 30.

35 A fuel pipe 50 leading to a main fuel supply is screwed into a boss 52 on housing 28 to conduct fuel to the fuel bowl 38. A passage 54 in the wall of housing 28 communicates with said boss and registers with a 40 passage in the frame 30 in which is screwed a nipple 56, as shown in Fig. 4. The passage through the nipple is restricted at 58 to form a seat for a valve 60, operated by a 45 float 62 to control the flow of fuel to bowl 38 in the usual way. The float is of hollow metal construction, semi-annular in form, and provided with arms 64 and 66 secured to its two ends by solder or otherwise. These 50 arms are pivoted on pins 68 which are loosely mounted in a depending portion of the frame 32, and are held in position in said frame when the device is assembled by engagement of the fuel bowl with the outer ends of said 55 pins, as shown in Fig. 9. The valve 60 rests on the arm 64 and is opened and closed during vertical oscillation of the float to regulate the level of liquid in the fuel bowl in a manner well known.

60 Fuel is conveyed from the fuel bowl to the primary carburetors which will be more fully described later through an angular passage 65 bored in a portion of the frame 30 as indicated in Fig. 10. The lower horizontal portion of the passage connects with a ver-

tical passage 72 formed in a projecting part of the frame 30 as shown in Figs. 3 and 10. A calibrated plug 74 is screwed into the lower end of passage 72 and controls the flow of fuel at low and intermediate speeds, all of 70 the fuel flowing through said plug up to an engine speed corresponding to a vehicular speed 55-60 miles per hour on a level. Thus the plug 74 meters or regulates the flow of fuel per unit of time to the primary carburetors up to the vehicular speed above referred to, after which a fuel valve 76 received in the upper part of the vertical passage 72, and normally seated on a restriction 78 in said passage is lifted by means herein-after described to permit fuel to flow through an auxiliary fuel port 80, past valve seat 78 to passage 70 to augment the fuel flowing through the plug 74. 75

80 The fuel passage 70, at its upper end communicates with a horizontal fuel canal 82 formed in the upper face of the frame 30. This canal communicates with three calibrated plugs 84, screwed into the lower face of the housing 28 and each connecting with a vertical passage 86 bored in the wall of the housing 28 as shown in Fig. 6. Each of said passages 86 communicate with one of three parallel primary carburetors, indicated in their entirety by the numeral 88, to supply fuel thereto. After the valve 76 is lifted as 85 previously described to render the port 80 effective to admit fuel, the calibrated plugs 84 meter or regulate the flow of fuel per unit of time to the primary carburetors. 90

95 Each of the primary carburetors comprises an angular mixture passage having a horizontal outlet portion 90 and a vertical inlet portion 92. These passages are in substantially parallel vertical planes and are bored in the bottom wall of the main housing 28 which may be termed the distributor block, for convenience. The vertical inlets 92 communicate with the main air chamber 94, formed in housing 28 and more fully described later, all of the air flowing through the primary carburetors at all engine speeds being taken from said main air chamber, in which the suction at any engine speed is a static suction determined by the action of a spring held main air valve, the construction and operation of which will be described in detail hereinafter. 100

105 110 Associated with each primary carburetor to supply fuel thereto is a fuel passage 86, previously described. Each passage 86 is formed in the wall of housing 28 closely adjacent and substantially parallel to the vertical portion 92 of the primary mixture passage with which said passage 86 is associated. Each passage 86 is provided at its lower end with a small fuel inlet orifice 96, which admits fuel to the passage 92 for low speed operation. Each passage 86 communicates 115 with a horizontal passage 98, bored in the 120

wall of housing 28 a short distance above the orifice 96, and having its outer end closed by a plug 100. The diameter of the passage 98 at its point of joinder with the passage 86, 5 is appreciably greater than that of passage 86, and said passage 98 is provided with a restricted end 102 communicating with the passage 92 and constituting a main fuel inlet orifice therefor, which is ineffective at low 10 speeds but comes into operation at higher speeds to augment the flow of fuel from the inlet 96. Bored in the wall of the housing 28 are three passages 104 connecting with the passages 98, which connect said passages 15 98 with the main air chamber 94, to communicate the suction of said chamber to the passages 98.

It will be obvious on consideration of the above described structure, that the suction, 20 which is effective at any engine speed, to lift fuel from the fuel bowl through the metering plugs 74 and 84 to the fuel feeding orifice 96 and 102 is substantially the static suction maintained in the air chamber 94, rather 25 than the suction of the primary mixture passages which is dependent primarily on the velocity of flow through such passages.

The passages 86 are in communication with the air chamber 94 through passages 98 and 30 104, and communicate with the primary mixture passages solely by means of the orifices 96 and 102, the combined area of which is considerably less than the cross sectional area of either passage 98 or 104.

35 In order for a velocity head to be created in the passages 86 and thus become effective to control the fuel flow, it would be necessary for air to flow from chamber 94, through passages 98 and 104 and through the orifices 40 96 and 102 to the primary mixture passages at high velocity. While there is a greater degree of vacuum maintained in the mixture passages than in chamber 94 and a flow of air will take place through the various passages as described above the velocity of such flow can never be sufficient to create a velocity head because the area of passages 98 and 104 is much greater than the combined area of holes 96 and 102. A current of air will be 45 moving through passages 98 and 104, but at all points between orifices 96 and 102, and the connection of passage 104 with the air chamber 94 the pressure will be substantially that of the air chamber at all engine speeds.

50 Since air can enter the passage 98 through the passage 104 so much more rapidly than it can be withdrawn therefrom through orifices 92 and 96 the velocity of flow through passages 104 and 98 must necessarily be low, 55 no matter how much greater vacuum is maintained in the primary mixture passages than in chamber 94. Obviously, therefore, the static suction of the chamber 94 which is communicated to the passages 86 through passages 98 and 104 must be the controlling fac-

tor effecting the flow of fuel to the passages 86, under all conditions of engine operations and speed.

The flow of primary fuel mixture through the primary carburetors is controlled by 70 means of a single primary throttle valve 106, which extends across all of the horizontal passages 90 and has grooves 108 formed therein which register with the said passages 90 as indicated in Fig. 8. This throttle is journaled in a suitable recess 110 of the same diameter as the throttle bored in the bottom wall of the housing 28. The ends of the throttle are reduced in size to form spin- 75 dles 112 and 114, which project beyond the walls of housing 28, and on which are secured, by set screws, certain valve operating connections hereinafter more fully described. These valve operating connections engage the outer walls of housing 28 and prevent 80 any longitudinal movement of the primary throttle, maintaining the grooves 108 in accurate registry with the passages 90.

The passages 90 connect, at their posterior ends, with passages 91 formed in the manifold wall and are associated with pipes which convey the primary mixture to secondary mixing chambers where it is mixed with additional or secondary air during operation of the engine at higher speeds. These passages 91 are not a part of the main carburetor, 85 but, as indicated, are formed in the wall of the air manifold, the latter with the conduits formed therein and pipes associated therewith, being manufactured as a unit separate 90 from the carburetor.

All of the air admitted to either primary or secondary mixing chambers, except a very small quantity which is admitted when the choke lever is operated to facilitate starting, 105 enters the carburetor through an air inlet horn 116, secured by screws 118 to the top of housing 28, and adapted to be connected to an air cleaner or other form of air intake connection. The horn 116 is provided with a restricted throat 120 at the apex of two conical surfaces 122 and 124, the surface 124 providing a seat for a valve 126, which controls the entry of air into chamber 94, which is held against its seat when the engine is not 110 running by a compression spring 128.

The valve 126 is secured to a coupling member 130 which is pinned to the upper end of a valve stem 132, slidably mounted in a guide sleeve 134, secured at its lower end in an orifice formed in the bottom wall of the housing 28 and is supported by a flanged plug 136 which fits tightly within a cylindrical recess 138 formed in the wall of the housing 28. The guide sleeve is forced downwardly into the plug until a shoulder 140 thereon engages the upper face of said plug. That part of the guide sleeve 134 above the plug 136 is enlarged and slidably mounted thereon is a 125 concentric sleeve 142, having a flange 144 130

secured to its lower end which provides a support for one end of the compression spring 128.

A choke lever 146 is pivoted by means 5 of a pin 148 mounted in bosses 150 projecting from the housing 28. The lever 146 projects through the wall of the housing and the inner end of said lever underlies the flange 144 as shown in Fig. 7. If the lever 146 is 10 moved to the position shown in Fig. 13, the sleeve 142 will be lifted and the spring 128 compressed. By partial operation of the choke lever the force of the spring 128 tending to prevent opening of the valve may be 15 regulated as desired, and a complete operation of the said choke lever will move the sleeve 142 upwardly into engagement with the valve 126, holding said valve entirely closed for starting of the engine.

20 It is necessary, however, for some air to be admitted when the carburetor is choked, to carry the liquid fuel to the engine cylinders and to form with said fuel a mixture which will burn. Heretofore a small fixed port has 25 been provided or the air valve has been allowed to open a slight distance to admit a small quantity of air when the choke mechanism is operated. Both of these means for admitting air have, however, caused improper proportioning of the mixture. It will be obvious that if the air valve spring is of proper tension to admit the correct amount of air as the throttle is opened through different degrees, any admission of 30 additional air through a fixed port or any means to open the valve slightly on starting will cause an excess of air to be admitted to the carburetor. This excess of air constitutes a greater proportion of the whole quantity of air admitted at low speeds than at 35 higher speeds, resulting in greater disturbance of correct mixture proportions at low speeds. In the device disclosed means are provided to admit a small amount of air 40 when the choke is operated, but which is rendered ineffective as soon as the choke mechanism is moved to its normal inoperative position, to prevent admission of this excess air during normal operation of the carburetor. For this purpose the choke 45 lever is provided with a flat surface 152 adjacent its pivotal mounting. When the lever is operated to hold the air valve closed and occupies the position shown in Fig. 13 the 50 surface 152 occupies a position such as to leave a small passage between the wall of the housing 28 and said flat surface, permitting the entry of a small quantity of air into the housing. When the choke lever is moved to 55 its normal position, the curved surface of the choke lever hub is brought into engagement with the similarly curved surface of the housing wall to close the passage above described and prevent admission of air there- 60 through.

To determine the normal inoperative position of the choke a set screw 154 is screwed into a lug 156 cast integral with lever 146 and is adapted to engage the wall of housing 28 to limit the movement of said lever toward 70 the wall. To yieldingly retain the set screw in any adjusted position a pointed flat spring 158 is riveted or secured in any other desirable way to the lever 146 so that the pointed end thereof engages the knurled head of set 75 screw 154.

To prevent fluttering of the air valve and to retard its movement toward open position for purposes of acceleration, a dash pot is provided including a cylinder 160 positioned within the fuel bowl and formed in a depending part of the frame 30. Received within the cylinder is a piston 162 slidably mounted on a sleeve 164 secured by a pin 166 to the lower end of the valve stem 132 and provided at its lower end with a flange 168 having an annular rim 170 formed on its upper face. The piston is normally held seated on said rim by a compression spring 171 received between an up-turned annular flange 172 surrounding the central opening in the piston in which said sleeve 164 is received, and a collar 174 screwed on the upper end of the sleeve. Holes 176 are provided in the bottom of the piston 162 to permit passage of fuel therethrough for the purpose of relieving the dash pot and permitting rapid opening of the air valve under certain operating conditions to be later described.

The bottom of the cylinder 160 is closed by a cap 178 soldered, or otherwise secured to the cylinder walls, so as to form a tight joint. At the center of the cap is a valve cage 180 having a fuel inlet orifice 182 therein. A check valve 184 is provided within the valve cage to permit flow of fuel into the cylinder on the up stroke of piston 162, but preventing out flow of fuel on the down stroke of said piston.

During operation at all engine speeds below that corresponding to a vehicular speed of 20-25 miles per hour on a level all the air entering the air manifold passes through the primary carburetors, the mixture formed therein being of properly combustible proportions. At speeds in excess of that mentioned, however, the primary mixture passages are of insufficient capacity to provide a sufficient quantity of mixture to the engine cylinders, and unless additional air were admitted to the engine cylinders the mixture entering the cylinders would be under such a high vacuum that a serious loss in volumetric efficiency would result. To obviate this difficulty the valves controlling the flow of air through the secondary air passage are opened after the engine speed referred to has been reached.

Flow of air through the secondary air pas- 130

sage is controlled by two valves, a manually operated butterfly throttle 186 and a suction operated valve 188. The throttle 186 is fixed on a shaft 190, journalled for rotation in the 5 walls of the housing 28, and is operated simultaneously with the primary throttle 106 by means of connections hereinafter fully described. The valve 188 is fixed on a shaft 192 also journalled in the walls of housing 28 10 and positioned off center with respect to the valve, a greater portion of the valve being below the shaft than above. This valve is operated by engine suction and its operation is controlled by devices described later. 15

The mechanism for operating the throttle valves will now be described. Adjustably secured to the spindle 112 on the primary throttle, by means of a set screw 194 or other suitable means is an operating lever 196, one 20 arm of which, is provided with an eye 198 in which is adapted to be connected a Bowden wire or other suitable connection extending to a point convenient to the operator. An arm 200 of said lever has pivotally connect- 25 ed thereto by a bolt 202 a square tube 204, the bolt passing through an ear 206 projecting from said tube. A slot 208 is provided in the wall of the tube adjacent the housing 28 and projecting through the slot is the 30 shank of a bolt 210, secured in one end of an operating arm 212 adjustably secured to the end of shaft 190 by a set screw 214. The lower end of the tube 204 is closed and received in said tube between the closed end and 35 a bent metal cap 213 freely slidable in the tube is a compression spring 215 which tends to hold the bolt 210 in the upper end of slot 208 at all times. When, however, the lever 196 is moved in a clockwise direction to close 40 the two throttles, the secondary throttle 186 reaches closed position before the primary throttle. During subsequent clockwise move- 45 ment of the lever 196 to close the primary throttle, the spring 215 is compressed and the square tube 204 is moved upwardly, so 50 that when both throttles are closed the parts are in the position shown in Fig. 14 with the bolt 210 positioned in the lower end of the slot 208. The closing movement of the pri- 55 mary throttle may be limited as desired by means of a stop screw 216 adjustable in a lug 218 projecting from the housing 28 and held in adjusted position by a lock nut 220. The screw is adapted to be engaged by a toe 222 60 projecting laterally from an arm 224 of the lever 196 as the latter is moved in a clockwise direction.

It will be clear that the pin and slot connection described above constitutes a lost motion connection between the two throttle valves permitting a definite amount of operation of the primary throttle entirely independent of the secondary throttle. When 65 the throttles are to be opened, the lever 196 is moved in a counter clockwise direction

and during the first part of the movement of said arm the primary throttle is opened without corresponding movement of the secondary throttle, until the tube 204 has moved downwardly enough to bring the bolt 210 into engagement with the upper end of slot 208, after which the two throttles are moved simultaneously. In the device disclosed herein the parts are so proportioned that the primary throttle opens to a position giving an engine speed corresponding to a vehicular speed of 20-25 miles per hour before the bolt 210 is engaged by the upper end of slot 208 to open the secondary throttle. 70

When the secondary throttle 186 is opened the suction in the air chamber 94 below the air valve 120 is greatly increased resulting in so great an inrush of air that, although the opening movement of the air valve is to some extent retarded, the flow of air into the air manifold past the secondary throttle 186 would be so great as to temporarily lean the mixture unless some means were provided to retard the flow of air through the secondary air passage. This action is due to the fact 80 that the primary mixture flows more slowly than pure air because of its greater density. Moreover, whenever either throttle is opened to accelerate a richer mixture is necessary 85 for a short interval of time, and means de- 90 scribed in detail hereinafter, is provided to force an additional quantity of fuel into the primary mixture passages whenever either throttle is opened for acceleration to provide a mixture of desired proportions. Owing to 95 the density of this rich primary mixture it requires an appreciable time to convey said mixture from the primary mixture passages, and the lower the pressure differential be- 100 tween the inlet and outlet ends of said primary mixing tubes the greater time interval required. On opening of the secondary 105 throttle 186, there would be an inrush of air past said throttle which would not only tend to dilute the mixture as above set forth but would cause a drop in the pressure differential between the two ends of the primary tubes. This would increase the time interval necessary for the primary mixture to reach 110 the secondary mixing chambers, and since the air is much lighter than the primary mixture, would result in the secondary air reaching the secondary mixing chambers before the enriched primary mixture causing a 115 starving of the motor. 120

The suction operated air valve 188 is therefore retarded during its opening movements for two reasons: first for producing at all times, when the throttle 186 is open, a sufficient pressure differential between the inlet and outlet ends of the primary mixing tubes to create a velocity of flow through these tubes great enough to transport the primary mixture from the primary mixing chambers to the secondary mixing chambers substan- 125 130

tially instantaneously: second, to prevent admission of a sufficient quantity of air through the secondary air passage to temperarily lean the mixture.

5 To control the movement of the air valve 188 said air valve has an arm 225 secured to its anterior side, as shown in Figs. 6 and 11 by brazing or in any other suitable way. The free end of this arm is pivotally connected to a short link 226 by a cotter pin 228 which extends through a short slot 230 in the link and a hole in the arm. The link 226 is pivotally connected to a bifurcated head 232 screwed on the end of a piston rod 234, and provided with two upstanding arms 236, each of which has a slot 238 formed therein. A cotter pin 240 extends through said slots and a hole in the lower end of link 226 which is received between the two arms when the parts 20 are connected together as shown in Fig. 11.

The piston rod is loosely received in a bore 242 in the bottom of housing 28, the bore providing a guide for the rod during vertical movements thereof. Pinned to the 25 lower end of the rod 234 is a sleeve 242 and slidably mounted on the sleeve is a piston 244 which fits within a dash pot cylinder 246, closed at its lower end by a cap 248, secured to the cylinder in any desirable way to 30 provide a fluid tight joint. The piston is normally held in its uppermost position to hold the valve closed by a spring 250 and opening movement of the valve is opposed by the force of the spring and the upward 35 pressure against the piston of the liquid in cylinder 246 below said piston, liquid fuel is admitted to said cylinder from the float chamber by leakage around the said piston and through a passage way formed between 40 the rod 234 and sleeve 242, the rod being somewhat smaller than the internal diameter of said sleeve. A check valve 252 is seated in the enlarged lower end of the sleeve 242 and operates to prevent flow of fuel from the 45 dash pot cylinder to the above described passage on downward movement of the piston, while permitting passage of fuel into the cylinder as the piston moves up. Any suitable means may be substituted for the spring 50 250 so as to return the piston 244 to its normal position when the air throttle is closed.

The sleeve 242 is provided with a flange 55 254 having an annular rim 256 formed on its upper face against which the piston is normally held seated by a spring 258 received between an upturned annular flange 260 surrounding the central opening in the piston through which sleeve 242 passes and a collar 262 screwed on the upper end of the sleeve. 60 Holes 264 are provided in the bottom of the piston to permit passage of fuel through the piston when the latter is lifted from the annular rim 256, under certain operating conditions hereinafter described, to relieve the 65 dashpot and permit rapid opening of the

valve. During normal operation the piston is seated on the rim 256, the piston and rim constituting a valve, preventing flow of fuel through the piston and enabling the dashpot to retard the opening movement of valve 188 70 during opening movement of the throttles.

Under certain operating conditions, when the suction effective to open the valves 126 and 188 is very suddenly and very greatly increased the pistons 162 and 244 are both 75 moved downward so rapidly that the resistance to their motion is great enough to overcome the pressure of springs 171 and 258 and lift the pistons 162 and 244 from the annular rims 170 and 258 respectively thus permitting fuel to flow from below both of said pistons and through the holes therein allowing both valves 126 and 188 to open freely. After the pistons are lifted from the rims 170 and 256 80 they will not reengage such rims until the pressures against the lower side of the pistons become less than the pressures of the springs which normally hold the pistons in engagement with said rims. It will be clear that the pressures required to hold the pistons above the rims are much less than the pressures required to initially lift the pistons, because such pressures are effective on the entire lower face of each piston while the pressures effective to initially lift the pistons are applied only to those portions of the pistons which extend beyond the flanges 168 and 254. As an example of operating conditions when the pistons will be lifted as described, it may be assumed that the vehicle is coasting down hill at a speed of 35 to 40 miles 85 per hour with the secondary throttle 186 closed and clutch engaged. If an up-grade is reached and the throttle is opened it is not desirable to retard the opening of either of the air valves 126 and 188 because the engine is already running at speed and no mixture enrichment is necessary, but sufficient air must be admitted to provide the necessary 90 pressure of charge to give the necessary power.

It will be noted that the device disclosed herein differs from those disclosed in the prior applications referred to above in the construction of the throttle 186 and valve 188. In this device these valves are in no way connected, the valve 188 being operated entirely by engine suction, while in the earlier devices, said valves were connected by a form of yielding operating connection, whereby the manually operated throttle tended to operate the other valve. The construction disclosed herein is considerably simpler, but the yielding connection previously used, or other form of connection, may be embodied herein to aid in controlling the opening movement 105 of the valve 188, if desired.

As indicated hereinbefore a device is provided for enriching the mixture whenever the throttle is opened for purposes of acceleration. This device comprises a pump as- 110

sociated with the main air valve 126 and effective when said valve is opened to inject a given charge of fuel into the primary mixture passages. This pump comprises a small auxiliary cylinder 264 cast integral with and on one side of the main dashpot cylinder 160, the lower ends of said cylinders being connected by a passage 266 through which fuel flows from the cylinder 160 into cylinder 264.

10 The top of the auxiliary cylinder is partially closed by an apertured plug 268 and slidably mounted within the said cylinder is a piston 270, provided with a vertical bore 272 therein, connected at its upper end by a series of small 15 passages 274 with an annular channel 276 formed in the periphery of the piston. Normally when the parts within the carburetor are at rest at any engine speed the piston 270 occupies the position shown in Fig. 6 at the 20 bottom of the auxiliary cylinder, seated on a flange or ledge 278 projecting inwardly from the cylinder wall and closing a port 280 connecting the interior of the auxiliary cylinder with the main fuel chamber. In this position 25 of the piston the channel 276 connects with a right angled passage 282 bored in a portion of the frame 30 cast integral with the auxiliary cylinder. This passage is connected by means of two passages 284 with a fuel channel or canal 286 formed in the upper 30 face of the frame 30 as shown in Figs. 6 and 12. Three outlet passages 288 having restricted upper ends 290 connect the fuel channel 286 with the primary mixing chambers at 35 a point immediately below the axis of the primary throttle valve. Bored in the bottom wall of the housing 28 are two passages 292 connecting the upper part of the float chamber with the fuel channel 286, to admit air to 40 said fuel channel from the space above the fuel in the float chamber, said space being in communication with the outside atmosphere through the elongated passage 294 in the wall of housing 28 as shown in Figs. 4 and 7.

45 The above described pump operates as follows. With the parts at rest, at whatever speed the engine may be running, the piston 270 occupies the position shown in Fig. 6, with the channel 276 in registry with the fuel 50 passage 282. Any opening of the throttle for acceleration will be accompanied by a downward movement of the dash pot piston 162, which will force fuel through the passages 266, 272, 274, channel 276 and passage 282 to the channel 286 where it is mixed with air to form a super-rich emulsion of fuel and air which is drawn through the passages 288 into the primary mixture passages to enrich the mixture therein. During this 55 action a pressure is built up on the fuel which will lift the auxiliary piston when the pressure reaches a predetermined degree. The lifting of the auxiliary piston moves the channel 276 out of registry with the passage 282 and simultaneously opens

the port 280, so that any further downward movement of the piston 162 will merely force fuel from the dashpot cylinder 160, back into the main fuel chamber through the port 280. After the air valve comes to rest the piston 270 will fall by action of gravity and again assume the position shown in Fig. 6, so that a subsequent opening movement of the throttle and downward movement of the air valve will again pump additional fuel into the primary mixture passages as described. Since the pumping action is terminated whenever the pressure effective to lift the piston 270 is reached, and takes place whenever the piston 162 moves downwardly it should be clear that the pump is effective to force a predetermined charge of fuel into the primary mixture passages to enrich the mixture whenever the throttle is opened. This form of accelerator pump is deemed more desirable than those shown in the prior applications mentioned above, which are variably effective, and if operative to supply the proper amount of fuel when accelerating at one speed, may supply too little or too much fuel when accelerating at other speeds.

In addition to the accelerator pump, mechanically operated means are provided to admit additional fuel at high engine speeds and to continue admitting such fuel as long as the engine runs at such speeds, to give the power necessary for proper operation at high engine speed. This means includes the fuel valve 76, hereinbefore briefly mentioned, which is opened at an engine speed corresponding to a vehicular speed of approximately 50 miles per hour on a level, to admit additional flow of fuel to the fuel passage 70 through orifice 80. The valve 76, during operation at all speeds up to that referred to, is held closed by a spring 300 as shown in Figs. 3 and 10. At its upper end the valve stem is formed with a reduced neck 302 which is engaged in a slot formed in an ear 304 projecting inwardly toward the housing 28 from one end of a lever 306, pivoted on a screw 308 screwed in said housing. At its opposite end the lever 306 is provided with an outwardly projecting ear 310 which underlies a cam 312 adjustably secured by a set screw 314 on the spindle 114 of the primary throttle. The cam is formed with two high points 316 and 318 having a concentric surface 320 between said high points. In Fig. 3 the cam is shown in the position it occupies when the primary throttle is completely closed. As the primary throttle is opened the cam moves in a clockwise direction from the position shown in Fig. 3 and since the low surface of the cam between the two points 316 and 318 is almost concentric with an abrupt rise at the point 316, no motion of the valve 76 is effected until the point 316 of the cam engages the ear 308, which occurs at a speed of approximately 50 miles per hour.

5 curs when the engine reaches the speed previously mentioned. Since the rise of the cam point 316 is very abrupt the valve 76 is opened wide during a very slight movement of the cam and is held in that same position by the surface 320 during the entire remaining movement of the cam until maximum speed is reached.

10 The means for conveying the primary mixture from the carburetor unit to the secondary mixing chambers and the construction of such mixing chambers will now be described. While these devices are of substantially the same construction as in the carburetors shown in the prior applications 15 above referred to and constitute no part of the present invention, they are briefly described herein to enable the invention to be readily understood without reference to other disclosures.

20 Each of the outside primary mixture passages 90 is in registry with a passage 91 of elbow shape formed in the manifold 20. Screwed into the opposite end of each elbow shaped passage is a pipe 324, the opposite end of which is screwed into an elbow 326, having a flange 328 attached to a flat surface on a boss 330 projecting from the manifold, by screws 332. The passage through each elbow 326 is in direct communication with a primary mixture pipe 334 extending through each outer branch 24 of the manifold. The center one of the primary mixture passages 90 is in direct communication with the primary mixture pipe 334 received in the middle passage 91 and extending through the central branch 24 of the manifold to the secondary mixing chamber formed therein.

25 It has been found advantageous to surround the end of each primary mixture pipe 334 with a Venturi tube 336 which constitutes the secondary mixing chamber. An external rib 338 is provided on the Venturi tube and is received, when the manifold is attached to the engine block, in a recess 340 in the end of the manifold and a corresponding recess (not shown) in the block. The venturi is held fixed in position by a shoulder 342 on the manifold and a corresponding shoulder on the engine block engaging opposite sides of the rib 338. The Venturi tube not only increases the velocity of air flowing through the branches of the manifold at the inlets of the pipes 334 which results in better mixing of the fuel and air in the secondary mixing chambers, but also increases the suction at the end of the pipes 334, thus increasing the velocity of the primary mixing flowing through such pipes which aids in acceleration of the engine. Other flow accelerating means may be substituted for the venturi if desired.

30 It will be noted on examination of Fig. 8 that the stem 132 of the main air valve in this device and the guide sleeve therefor pass

35 through the middle one of the three primary mixture passages 90. To prevent any increase in velocity of the primary mixture at this point with resulting variation in vacuum conditions in this mixture passage, said passage is enlarged immediately adjacent the air valve stem as indicated at 350 so that the area of the passage around the guide sleeve is substantially the same as the area of the passage elsewhere throughout its length. 70

40 The advantages secured by elimination of the velocity head as the controlling factor regulating fuel flow will be best understood by a consideration of the difficulties caused by the presence of a velocity head in prior carburetors of this type, such as those disclosed in the above mentioned applications. Owing to the presence of the velocity head 45 the fuel jets in such carburetors are calibrated somewhat smaller than they should be to give the economical fuel mixture ratio of 15½ to 1, proper for medium speeds, if the flow of fuel from said jets were determined by air valve suction. Up to an engine speed of substantially 1000 R. P. M. part throttle 50 the velocity head is increased slowly and is effective to produce a flow from the jets which is approximately correct to give the desired mixture ratio above referred to. At, engine speeds above 1000 R. P. M. part 55 throttle the velocity head builds up so rapidly that the fuel flow at an engine speed corresponding to 30 miles per hour vehicular speed, would be as great as the engine requires at 2000 R. P. M. open throttle. 60

65 The velocity effect on the jets must be reduced, therefore, at speeds beyond 1000 R. P. M. and to do this the secondary throttle corresponding to the valve 186 of this device is connected to the primary throttle and 70 timed to begin opening at about 1000 R. P. M. which corresponds to a vehicular speed of 20 miles per hour. Owing to the large diameter of the secondary throttle and consequent rapid increase in volume of air flowing past said throttle per degree of rotation, the velocity of air flowing past the jets is very rapidly lowered being practically eliminated at something more than 1500 R. P. M. Since the jets are calibrated to give the proper fuel mixture up to 1000 R. P. M. when the flow therefrom is controlled by the velocity, the reduction in 75 velocity head at speeds above 1000 R. P. M. when the secondary throttle is open causes a reduction in fuel flow below that necessary for a 15½ to 1 mixture of air and fuel. This necessitates an additional flow of fuel which is accomplished by opening a needle valve 80 and permitting fuel to flow through an auxiliary fuel passage. The needle valve is lifted through the cam 312, the contour of which is designed to admit just enough additional fuel to compensate for the loss in suction on 85 120

the fuel jets due to reduction in velocity head effective thereon.

In order to attain the desired result, that is, secure a fuel mixture in the proportions of 15½ to 1, the two throttles must be accurately synchronized, not only with relation to each other, but also to the needle valve. The cam which lifts the needle must be correct in contour, must be accurately located 10 with reference to its follower and the latter must be also of exactly the right size and located in exactly the right position. Since it is attempted to correct the velocity head which is a variable and unstable force by a 15 mechanically operated means it is difficult to obtain the synchronization of operation above referred to, and if such synchronization is secured it will be disturbed by wear or by dimensional variations, or by any of 20 the parts becoming loose.

By eliminating the velocity head at the jets, and employing a metering jet calibrated to permit flow of fuel sufficient to give a fuel mixture in the proportion of 15½ to 1 when 25 the fuel flow is governed by engine suction as determined by the spring held main air valve, the variation in fuel flow on opening of the secondary throttle will disappear and there will be no need to open the needle 30 valve to admit additional fuel except for full throttle operation. Therefore, the need of accurate timing of operation of the two throttles with each other, or with the needle valve will disappear.

35 In Fig. 15 is shown a modified form of fuel inlet means, by means of which the effect of impact of the air entering the main air intake on the flow of fuel from said fuel inlet is prevented altogether. In the form 40 shown in Figs. 1 to 14 the impact of the entering air will produce little or no effect on the flow of fuel because the passage 104 is considerably offset from the direct path of air flow which is through the passages 92. 45 However, in the modification shown in Fig. 15 means are provided to prevent any possibility of a disturbance in the fuel flow due to air impact. To this end the intake of passage 104 is not in the floor of the air 50 chamber as shown in Fig. 6. Instead, the wall of housing 28 is cast with a thickened portion 360 extending above the floor of the air chamber and projecting into the chamber. The passage 104 is bored in this portion 55 360 of the housing wall and communicates with the jet through a passage 362 formed in the vertical wall of the part 360. The bore 360 is thus closed at its upper end and communicates with the air chamber through the 60 passage 362 which is substantially perpendicular to the path of the air flowing through such chamber and the effect of impact is entirely prevented.

65 It will be noted that the device disclosed herein is symmetrical, that is, the air mani-

fold and the carburetor are so designed that when the carburetor unit is assembled and attached to the manifold a vertical plane passing through the axis of the middle branch of the manifold substantially divides the carburetor in two equal parts. In other words, the main parts of the carburetor unit, namely the air chamber 94, the secondary air passage 22, the distributor block, frame 30 and fuel reservoir 38 are divided by such a 70 vertical plane into substantially equal parts lying on opposite sides thereof. Two important advantages are secured by this symmetrical construction. First the formation of eddies and resulting turbulence in the ingoing mixture is much reduced by comparison with the device shown in the above mentioned applications, making it easier to control the mixture proportions and distribution. Second, the structure is much simplified and the cost of manufacture materially 75 reduced.

80 While the form of embodiment of the present invention as herein disclosed, constitutes a preferred form, it is to be understood that other forms might be adopted, all coming within the scope of the claims 85 which follow.

90 What is claimed is as follows:

95 1. A charge forming device for internal combustion engines comprising a mixing chamber, through which air is adapted to pass at high velocity, a fuel passage, fuel inlet means connecting said fuel passage and the mixing chamber, an air chamber for supplying air to said mixing chamber, and means for making the static suction of the air chamber the dominant factor controlling the flow of fuel into the mixing chamber, comprising a passage connecting the air chamber and fuel passage which is of greater 100 size than said fuel inlet means.

105 2. A charge forming device for internal combustion engines comprising a mixing chamber through which air is adapted to pass at high velocity, a fuel passage, fuel inlet means connecting said fuel passage and the mixing chamber, an air chamber for supplying air to said mixing chamber, a spring held valve for controlling flow of air into said air chamber, and means whereby the tension of the air valve spring determines the suction effective to control the flow of fuel into said mixing chamber, said means comprising a 110 passage connecting the air chamber and said fuel passage which is of greater size than said fuel inlet means.

115 3. A charge forming device for internal combustion engines comprising an odd number of primary mixing chambers, means for supplying fuel and air to said chambers, a main air chamber positioned above said primary mixing chambers, an air valve admitting air to said chamber, a stem supporting 120 said valve and passing through the middle 125 of the primary mixing chambers.

one of said primary mixture passages, and an enlargement in said passage adjacent said stem, so that the unobstructed area of said passage is the same throughout its length.

5 4. A charge forming device for internal combustion engines comprising an air inlet chamber, a fuel reservoir, a plurality of secondary mixing chambers, a distributor block having a plurality of primary mixture passages formed therein and adapted to deliver primary mixture to a plurality of secondary mixing chambers, and a secondary air passage supplying air to said mixing chambers, said fuel reservoir, air inlet chamber, distributor block and secondary air passage being so arranged that the center of each lies in a single vertical plane.

20 5. A charge forming device for internal combustion engines, comprising a primary mixing chamber, an air chamber supplying air to said primary mixing chamber, a secondary mixing chamber into which the primary mixing chamber is adapted to deliver a primary mixture of fuel and air, and means 25 making the static suction within the air chamber the dominant factor controlling the supply of fuel to said primary mixing chamber, said means comprising a fuel supply passage having an outlet communicating with the primary mixing chamber and means for communicating the air chamber suction to said fuel passage.

30 6. A charge forming device for internal combustion engines, comprising a primary mixing chamber, an air chamber for supplying air to said primary mixing chamber under all operating conditions, and to said secondary mixing chamber under certain operating conditions, a valve for controlling the 35 flow of air from said chamber to the secondary mixing chamber, and means making the static suction within the air chamber the dominant factor controlling the supply of fuel to said primary mixing chamber, said 40 means comprising a fuel supply passage having an outlet communicating with the primary mixing chamber, and means for communicating the air chamber suction to said fuel passage.

45 7. A charge forming device for internal combustion engines, comprising a primary mixing chamber, an air chamber for supplying air to said primary mixing chamber under all operating conditions, and to said secondary mixing chamber under certain operating conditions, a valve for controlling the flow of air from said chamber to the secondary mixing chamber, a throttle for controlling the flow of primary mixture from 50 the primary mixing chamber, and means making the static suction within the air chamber the dominant factor controlling the supply of fuel to the primary mixing chamber, said means comprising a fuel supply passage formed in the wall of the main housing provided with an outlet communicating with the primary mixing chamber, an orifice communicating with the air chamber, and means shielding said orifice from the effect of impact of the air entering the air chamber.

55 8. A charge forming device for internal combustion engines, comprising a primary mixing chamber, an air chamber for supplying air to said primary mixing chamber under all operating conditions, and to said secondary mixing chamber under certain operating conditions, a valve for controlling the flow of air from said chamber to the secondary mixing chamber, a throttle for controlling the flow of primary mixture from the primary mixing chamber, means for operating said air valve by the throttle, and means making the static suction within the air chamber the dominant factor controlling the supply of fuel to the primary mixing chamber during the entire opening movement of said throttle and air valve, said means comprising a fuel passage having an outlet communicating with the primary mixing chamber, and means communicating the air chamber suction to said fuel passage.

60 9. A charge forming device for internal combustion engines, comprising a main housing, a primary mixing chamber formed therein, an air chamber supplying air to said primary mixing chamber, a secondary mixing chamber into which the primary mixing chamber is adapted to deliver a primary mixture of fuel and air, and means making the static suction within the air chamber the dominant factor controlling the supply of fuel to the primary mixing chamber, said means comprising a fuel supply passage having an outlet communicating with the primary mixing chamber, and means communicating the air chamber suction to said fuel passage.

65 10. A charge forming device for internal combustion engines, comprising a main housing, a primary mixing chamber formed therein, an air chamber supplying air to said primary mixing chamber, a secondary mixing chamber into which the primary mixing chamber is adapted to deliver a primary mixture of fuel and air, and means making the static suction within the air chamber the dominant factor controlling the supply of fuel to the primary mixing chamber, said means comprising a fuel supply passage formed in the wall of the main housing provided with an outlet communicating with the primary mixing chamber, and an orifice 70 communicating with the air chamber.

75 11. A charge forming device for internal combustion engines, comprising a main housing, a primary mixing chamber formed therein, an air chamber supplying air to said primary mixing chamber, a secondary mixing chamber into which the primary mixing chamber is adapted to deliver a primary mixture of fuel and air, and means making the static suction within the air chamber the dominant factor controlling the supply of fuel to the primary mixing chamber, said means comprising a fuel supply passage formed in the wall of the main housing provided with an outlet communicating with the primary mixing chamber, an orifice communicating with the air chamber, and means shielding said orifice from the effect of impact of the air entering the air chamber.

80 12. A charge forming device for internal combustion engines, comprising a main housing, a primary mixing chamber formed therein, an air chamber supplying air to said primary mixing chamber, a secondary mixing chamber into which the primary mixing chamber is adapted to deliver a primary mixture of fuel and air, and means making the static suction within the air chamber the dominant factor controlling the supply of fuel to the primary mixing chamber during the entire opening movement of said throttle and air valve, said means comprising a fuel passage having an outlet communicating with the primary mixing chamber, and means communicating the air chamber suction to said fuel passage.

- chamber is adapted to deliver a primary mixture of fuel and air, and means making the static suction within the air chamber the dominant factor controlling the supply of fuel to the primary mixing chamber, said means comprising a fuel supply passage formed in the wall of the main housing provided with an outlet communicating with the primary mixing chamber, an orifice communicating with the air chamber, the axis of said orifice being normal to the path of air entering the air chamber whereby the orifice is not subject to the effect of impact of the air entering the air chamber.
15. 12. A charge forming device for internal combustion engines, comprising a main housing having a plurality of primary mixing chambers formed therein, a plurality of secondary mixing chambers into which the primary mixing chambers are adapted to deliver a primary mixture of fuel and air, an air chamber supplying air to all of said primary mixing chambers, and means for making the static suction within the air chamber the dominant factor controlling the supply of fuel to all of said primary mixing chambers, said means comprising a plurality of fuel supply passages, each of which is provided with an outlet communicating with one of said primary mixture passages, and means for communicating the air chamber suction to all of said fuel passages.
15. 13. A charge forming device for internal combustion engines, comprising a main housing having a plurality of primary mixing chambers formed therein, a plurality of secondary mixing chambers into which the primary mixing chambers are adapted to deliver a primary mixture of fuel and air, an air chamber supplying air to all of said primary mixing chambers, and means for making the static suction within the air chamber the dominant factor controlling the supply of fuel to all of said primary mixing chambers, said means comprising a plurality of fuel supply passages, each of which is provided with an outlet communicating with one of said primary mixing chambers, and an air inlet of larger size than said outlet, all of said air inlets communicating with said air chamber.
15. 14. A charge forming device for internal combustion engines, comprising a main housing having a plurality of primary mixing chambers formed therein, a plurality of secondary mixing chambers into which the primary mixing chambers are adapted to deliver a primary mixture of fuel and air, an air chamber supplying air to all of said primary mixing chambers, and means for making the static suction within the air chamber the dominant factor controlling the supply of fuel to all of said primary mixing chambers, said means comprising a plurality of fuel supply passages, each of which is pro-
- vided with an outlet communicating with one of said primary mixing chambers, and an air inlet of larger size than said outlet, all of said outlets and all of said air inlets being of the same size respectively.
15. 15. A charge forming device for internal combustion engines, comprising a main housing having a plurality of primary mixing chambers formed therein, a plurality of secondary mixing chambers into which the primary mixing chambers are adapted to deliver a primary mixture of fuel and air, an air chamber supplying air to all of said primary mixing chambers, and means for making the static suction within the air chamber the dominant factor controlling the supply of fuel to all of said primary mixing chambers, said means comprising a plurality of fuel supply passages, each of which is adapted to supply fuel to one of the primary mixing chambers, outlet passages of the same length connecting the fuel supply passages with the associated primary mixing chambers, air inlets for all of said fuel supply passages communicating with said air chamber.
15. 16. A charge forming device for internal combustion engines, comprising a main housing having a plurality of primary mixing chambers formed therein, a plurality of secondary mixing chambers into which the primary mixing chambers are adapted to deliver a primary mixture of fuel and air, an air chamber supplying air to all of said primary mixing chambers, and means for making the static suction within the air chamber the dominant factor controlling the supply of fuel to all of said primary mixing chambers, said means comprising a plurality of fuel supply passages, each of which is provided with an outlet communicating with one of said primary mixture passages, and means for communicating the air chamber suction to all of said fuel passages, and a common fuel canal supplying fuel to all of said fuel passages.
- In testimony whereof I hereto affix my signature.
- WILFORD H. TEETER.
